(57) **CLAIM**

The ornamental design for a fire containment cargo cover and bag set, as shown and described.

DESCRIPTION

FIG. 1 is a perspective view of a fire containment cargo cover and bag set.

FIG. 2 is the right side view thereof.

FIG. 3 is the left side view thereof.

FIG. 4 is a front side view thereof.

FIG. 5 is a back side view thereof.

FIG. 6 is a top view thereof.

FIG. 7 is a bottom view thereof.

FIG. 8 is a perspective view of a bag.

FIG. 9 is a front side view thereof.

FIG. 10 is a back side view thereof.

FIG. 11 is a left side view thereof.

FIG. 12 is a right side view thereof.

FIG. 13 is a top view thereof; and,

FIG. 14 is a bottom view thereof.

The fire containment cargo cover is shown without the bag in FIGS. 1-7 for convenience of illustration. The bag is shown without the fire containment cargo cover in FIGS. 8-14 for convenience of illustration. The claimed design is shown in solid lines.
